UNITED STATES PATENT OFFICE

119,475

DESIGN FOR A COMBINED FERTILIZER DISTRIBUTOR AND CONTAINER

Frank F. Paskewitz, St. Paul, Minn., assignor to
Gro-Lux, Incorporated, Minneapolis, Minn.

Application October 15, 1938, Serial No. 80,481

Term of patent 7 years

To all whom it may concern:

Be it known that I, Frank F. Paskewitz, a citizen of the United States, residing at St. Paul, in the county of Ramsey and State of Minnesota, have invented a new, original, and ornamental Design for a Combined Fertilizer Distributor and Container, of which the following is a specification, reference being had to the accompanying drawing, forming part thereof, in which the figure is a perspective view of a combined fertilizer

distributor and container, showing my new design.

The characteristic features of my design reside in the cap and the member positioned transversely through the top of the cap.

I claim:

The ornamental design for a combined fertilizer distributor and container, as shown and described.

FRANK F. PASKEWITZ.
